UNITED STATES PATENT OFFICE

166,040

TELEVISION AND RADIO PROGRAM
HOLDER

Earl A. La Plante, Boston, Mass.

Application June 28, 1950, Serial No. 10,809

Term of patent 14 years

(Cl. D1—12)

To all whom it may concern:

Be it known that I, Earl A. La Plante, a citizen of the United States, residing at Boston, county of Suffolk and Commonwealth of Massachusetts, have invented a new, original, and ornamental Design for a Television and Radio Program Holder, of which the following is a specification, reference being had to the accompanying drawing, forming a part hereof.

In the drawings:

Fig. 1 is a front elevation of a television and radio program holder, showing my new design;

Fig. 2 is a side elevation of the same; and

Fig. 3 is a section on the line 3—3 of Fig. 1.

I claim:

The ornamental design for a television and radio program holder, substantially as shown.

EARL A. LA PLANTE.
